[57] ABSTRACT

A gong or bell attached to a door such that when a thief breaks open the door, a ball or like object having a rod extending therethrough and resting on a ledge which projects from the top of a frame for the door, falls along the rod as the ball or like object is pushed with the door out of a slot in the ledge and rings the gong or bell by striking it and a spring which prevents muffling of the sound.

FIG-1

FIG-2

FIG-3

BURGLAR ALARM

This is a continuation-in-part of Ser. No. 2,847 filed Jan. 12, 1979, now U.S. Pat. No. 4,203,383

BACKGROUND OF THE INVENTION

1. Field of the Invention

This invention relates to burglar alarms. More particularly, it relates to a non-electrical bell adapted to be affixed to a door in such a manner that it sounds when the door is opened.

2. Description of the Prior Art

U.S. Pat. No. 713,780 of MacDonald shows a door burglar alarm operated by a weight attached by means of a hook to a bar which fits between the door and the door jamb. When the door is opened the weight falls on a cap which explodes when hit by the weight. Bell, U.S. Pat. No. 1,483,708 teaches use of a ball fitting around a post which moves from one end of the post to the other when the post is turned over to give visual notice of a fare-box in which it is contained having been tampered with. Mohler, in U.S. Pat. No. 1,003,636 discloses a rod surrounded along part of its length by a spring, the rod having a hammer adapted to strike a bell when a refrigerator pan overflows. None of the foregoing teaches how to simply and efficiently sound an alarm when someone breaks into a house without danger to someone who might be at or near a door as it is broken through.

SUMMARY OF THE INVENTION

After extended investigation I have found that, by providing a removable ball or like object adapted to fall and strike a mechanical gong or bell when a door is opened, such complex structure and electrical connections may be avoided. In its broader aspects, my invention involves, as cooperative components, (1) a mechanical gong or bell adapted to be fastened to the inside of a door, (2) a bracket or ledge having a slot or groove therein, said bracket being adapted to be fastened to the top of said door frame, (3) a spherical, rectangular or like object having a hole therethrough and adapted to rest on said bracket except when the gong or bell is in use, (4) a rod adapted to be affixed at one end thereof to said gong or bell and to project through said slot and said hole toward the other end thereof when said object is resting on said bracket or ledge and (5) a spring encircling said rod near the bell end thereof where by the noise is not damped when said spherical, rectangular or like object strikes said spring and gong or bell. When installed on a door and door frame, the burglar alarm operates by the ball or similar object falling along the rod and sounding an alarm by ringing the gong or bell by striking it and the spring which encircles the rod along part of its length when the door is opened far enough for the rod to slip out of the slot or groove in the bracket or ledge and let the ball fall. When someone is at home during the daytime and does not wish to be disturbed by the alarm when another member of the family comes in, the ball may be left in a drawer or other suitable location, if desired. The aforesaid components, together with the necessary parts for the assembly thereof on a door and door frame, may make up a kit which may be used by a builder, carpenter, homeowner or other individual or group.

DESCRIPTION OF THE DRAWING AND OF THE PREFERRED EMBODIMENT

For a better understanding of the invention, reference 5 will now be made to the drawing, which forms a part hereof, and the description of which represents the preferred embodiment of the invention.

In the drawing,

FIG. 1 is a perspective elevation view from one side 10 of the door showing a door and door frame with the alarm apparatus of the invention in assembled form installed thereon.

FIG. 2 is an enlarged perspective view, of the alarm apparatus, partly sectional, taken at 2-2 of FIG. 1, 15 with door and frame in phantom, showing how the components are put together in a working manner and joined to the door and door frame.

FIG. 3 is a perspective view from an angle showing the components of the alarm device of the invention as 20 described hereinabove as well as screws which may be used to install the device.

The alarm apparatus as depicted in the drawing and adapted, as shown, to be installed on a door 10 and door frame 12, is made up of (1) a bell 14 with a rod 20 extending substantially vertically therefrom and entering a bracket 16 and continuing to point 41 where it may be bolted at 40. (Bracket 16 may have holes 19 therein and screws such as 18 to attach to door 10, the bracket 16 being joined to the bell 14 by spot welding or bolting, for example at 38) (2) a ball or similar object 22 with a hole 24 therethrough and (3) a ball-retaining bracket or ledge 26 having a slot or groove 32 therein, as well as notches 34 to assist in removing sections thereof, and screws 28 for inserting through holes 30 (as shown in FIG. 3) to join said bracket or ledge to the top of door frame 12. When the door is opened, ball 22 and rod 20 slip out of notch 32 with ball 22 falling down rod 20 in the direction shown by dotted arrow line 36 to dotted line position 22 and, upon striking bell 14 and a spring 35, sounds an alarm without dampening or muffling it.

While the invention has been described in terms of preferred embodiments, the claims appended hereto are intended to encompass all embodiments which fall within the spirit of the invention.

Having thus described my invention and certain preferred embodiments thereof, I claim:

1. An assembly of components in a kit, said assembly being adapted from assembly together and affixing to a door and door frame as a burglar alarm, said assembly comprising (1) a mechanical bell adapted to be fastened to the inside of a door, (2) a bracket having a slot therein, said bracket being adapted to be fastened to the top of said door frame, (3) an object having a hole therethrough and adapted to rest on said bracket, (4) a rod adapted to project through said slot and said hole and (5) a spring adapted to surround said rod near one end thereof.

2. The assembly of claim 1 wherein said object comprises a ball.

3. The assembly of claim 1 comprising additionally screws and at least one additional bracket adapted to attach the bell and rod to the door.

4. The assembly of claim 1 wherein said bracket has notches therein adapted for removing one or more sections thereof.

5. The assembly of claim 1 with said components assembled together and said assembly affixed to a door and door frame, whereby when said object falls and

strikes said mechanical bell and said spring it sounds an alarm as a result of said door being opened without the sound of the alarm being substantially muffled.

6. The assembly of claim 1 attached to a door and door frame as an integral unit and having said bracket 5 screwed to said door frame, said bell mounted on said

door by a second bracket and screws, said second bracket joined to said bell, and said rod extending through a hole in the top of said second bracket toward the bottom of said second bracket.
